Application March 14, 1934, Serial No. 715,436

22 Claims. (Cl. 234—53.5)

This invention relates to recorders in general.

The broad object of the invention is to provide an elapsed time recorder which is more adaptable and more flexible than prior recorders.

Another object is to provide an elapsed time recorder which is simple of construction and operation yet capable of accurately measuring and recording the elapsed time of a plurality of employees or operations or steps in the process of manufacture of an article.

A further object is to provide an elapsed time recorder capable of making a complete series of entries respecting a given job on a single job card and making the entries in such fashion that each entry is a complete check on the other entries.

A further object is to provide an elapsed time recorder which has a plurality of elapsed time units coacting with a single printing unit the operations of all of such units being controlled selectively by means of a single control lever or manual.

Another object is to provide an elapsed time recorder capable of making complete records of a single job on a single card, such as the workmen's numbers, the starting and finishing time of a plurality of operations or steps in the process of manufacture, and the elapsed time of each operation. The entries corresponding to the various operations may or may not be made in chronological order as desired.

A specific object is to provide an elapsed time recorder which can be manufactured very cheaply in any desired capacity.

Another specific object is to provide a multi-unit elapsed time recorder wherein the elapsed time units are more or less self contained and have few working parts all of which are of a simple nature and can be cheaply manufactured.

Briefly described, the invention includes a plurality of elapsed time units, a single printing unit, and a manual control lever adapted to selectively start, stop, and connect the elapsed time units to the printing unit to control the latter, operate the latter, and reset the selected elapsed time unit. The elapsed time units may be individual to workmen or machines and each is capable of measuring the time required to perform a predetermined operation or step in the process of manufacture or measure the operating time of a given production machine or workman. The printing unit is capable of making an entry on a card including the workman's number or the number of the machine, the starting or finishing times of the operation or step, and

the elapsed time, all under control of the single manual control lever. The recorder is so arranged that a plurality of registrations or entries can be made on a single record card so that such card will show a complete history of a job. The arrangement of the printing unit and the control connections is such that the recorder is adaptable to an infinite number of situations without material change in the construction of the recorder.

Various objects, features, and advantages of the invention other than those mentioned above will be pointed out in the following description and claims or will be apparent from a study of the description, claims, and drawings.

In said drawings:

Fig. 1 is a front elevation partly in section.

Fig. 2 is a plan view partly in section.

Fig. 3 is a vertical section taken on the line 3—3 in Fig. 1.

Fig. 4 is an enlarged vertical section on the line 4—4 in Fig. 2.

Fig. 5 is a vertical section on the line 5—5 in Fig. 1.

Fig. 6 is a detail view of the mechanism for controlling the card stop as viewed from left in Fig. 1.

Fig. 7 is a view similar to Fig. 5 but shows certain parts in operated position.

Fig. 8 is a view of a card adapted for use with the present invention.

Fig. 9 is a top plan view of the mechanism shown in Fig. 7.

Fig. 10 is an enlarged plan view partly in section, showing in operated position certain parts in Fig. 9.

Fig. 11 is a large scale elevation of certain parts shown in Fig. 5.

Fig. 12 is a large scale vertical section on the line 12—12 in Fig. 5.

Fig. 13 is a large scale plan view of certain parts shown in Fig. 9.

Essentially the invention consists, as briefly stated above, of a clock or timing unit of some kind, a plurality of elapsed time units adapted to be selectively connected to the clock or timing unit, and a printing mechanism adapted to be controlled by the elapsed time units. The latter are preferably constructed as more or less independent units in order to provide for flexibility of construction, and enable recorders of different capacities to be constructed on a production basis as desired. All the above basic elements or mechanisms are mounted on a common base 20 (Figs. 1, 2, and 4) having a number of verti-

cal parallel frames secured thereto comprising four main frames 21 to 24, inclusive, and a plurality of sub-frames or partition frames 25 which support the elapsed time units.

- 5 Any number of such units may be provided as desired but only ten have been shown in the drawings purely for convenience in illustration and economy of space. As there are ten elapsed time units there are provided eleven of the frames 25.
- 10 The recorder is enclosed by a casing 26 which rests on the base 20 and has an upwardly extending subcasing 27 which protects the timing unit or clock 28. The latter may take any desired form, that is, it may be a spring operated 15 clock, a synchronous motor type clock, or any well known form of magnetically operated secondary clock controlled by impulses from a remote master clock, or a combination of any of the foregoing may be used. For example, a spring 20 driven or synchronous motor driven clock or clock movement may operate contacts which control an electromagnetic secondary driving the elapsed time units. It will suffice to state here that, whatever form the timing unit or clock may 25 take, it drives a vertical shaft 29 (Fig. 2) projecting from the sub-casing 27 into the main casing 26 and, through gears 29a, drives a horizontal shaft 30 at the rate, in the illustrative embodiment of the invention, of one revolution in six 30 minutes. The shaft 30 is common to all the elapsed time units and furnishes sufficient power to drive any and all of them that may have been selectively coupled to said shaft in a manner to be explained more fully later herein.
- 35 The printing mechanism is mounted on frames 21, 22 and a bracket 31 at the left end of the machine (Figs. 1, 2, and 4) and includes type wheels 32 to 35, inclusive, having raised type which are both reversed and inverted. The type wheel 32 40 is adapted to print numbers identifying the elapsed time unit selected for controlling the printing mechanism.

These numbers may represent workmen's numbers, bench numbers, or even job numbers, 45 according to the system followed by the user of the recorder. In the present description it will be assumed that the type wheel 32 bears ten types ranging from "1" to "10" and represent workmen's numbers.

- 50 The type wheels 33, 34 are for printing the time of day when jobs or operations are started and finished, the wheel 33 being the hour wheel while 34 is the minutes wheel. Accordingly, there are twelve types on the wheel 33 and sixty types on 55 wheel 34, as usual. The type wheels 33, 34 may be driven by the vertical shaft 28 by suitable gearing (not shown) or they may be actuated by separate means synchronized with the clock 28 as, for instance, by a standard electromagnetic 60 secondary movement or a synchronous motor after a fashion common in time recorders.

The type wheel 35 is adapted to print the total elapsed time under control of a selected elapsed time unit and for that reason is secured to a 65 shaft 36 common to all the elapsed time units and journaled in frames 22 to 25, inclusive. This type wheel, in the illustrative embodiment of the invention, may have 119 types ranging from 0.0 to 70 11.8 to represent hours and tenths of hours up to 11.8 hours. Due to peculiarities in the construction of the recorder shown, the types do not cover the circumference of wheel 35 completely but there is a relatively large gap or blank space 75 between the 0.0 type and the 11.8 type, this dis-

tance being equivalent to 2 of an hour. In other words, the types are $\frac{1}{120}$ of a circumference apart. The reason for this construction will appear later.

The mechanisms for positioning type wheel 32 and taking an impression from the type wheels 32 to 35 will next be described as both are closely associated. Extending longitudinally of the recorder and journaled in frames 21, 24 is a shaft 37, secured to the left end (Figs. 1 and 2) of which is a gear 38 meshing with an idler gear 39. The latter meshes with a gear 40 fixed to a sleeve 41 secured to type wheel 32, the sleeve 41 being journaled on a short shaft 42 supported by frames 21, 22. The shaft 42 also supports the type wheels 33, 34. Secured to shaft 37 is a drum 43 which in length is approximately two thirds of the length of shaft 37. This drum has a spiral groove 44 by means of which said drum and hence type wheel 32 may be rotated differentially as will be seen presently.

Parallel with shaft 37 and journaled in frames 21, 24 is a shaft 45 which has a keyway cut therein which keyway has secured therein a key 46 of length at least equal to drum 43 and located opposite said drum. Slidably mounted on shaft 45 is a yoke 47 having a pin 48 projecting into groove 44. The yoke 47 is adapted to permit shaft 45 to rotate relative to said yoke, in spite of the presence of key 46. Mounted on the shaft 45 between the arms of yoke 47 is a hand lever 49 to which is secured a handle 50 and a pointer 51. The hand lever 49 extends through a wide horizontal slot 52 in the casing 26 and a horizontal slot 53 in a guide plate 54 partly covering the opening 52 and screwed to casing 26. The guide plate 54 has ten 35 vertical slots or notches 53a at spaced intervals and extending downwardly from the horizontal slot 53 (Fig. 1). Each notch has a number which corresponds to one of the types on type wheel 32.

The proportions and arrangement of the parts 40 just described are such that type wheel 32 is rotated whenever handle 50 is grasped and moved horizontally in slot 53, due to pin 48 riding in groove 44 and causing drum 43 and hence type wheel 32 to rotate. In other words, when pointer 45 45 coincides with any given number on the guide plate 54, the corresponding type on wheel 32 will be at the printing point and lever 49 will be immediately above the corresponding vertical slot 53a.

The key 46 is slidable in a keyway cut in the hub of handle 49 so that depression of the handle 50 to cause lever 49 to move down into slot 53a will also cause shaft 45 to rock in a counterclockwise direction (Fig. 4). Secured to the left hand 55 end of shaft 45 is a gear 55 which meshes with an idler 56. The latter meshes with a gear 57 secured to a shaft 58 journaled in frame 21 and bracket 31. Pinned to shaft 58 is an arm 59 to which is pivoted a latch 60 having a hook portion 61 normally engaging a lug 61 formed in a lever 62 loosely mounted on shaft 58. The lower arm 63 of lever 62 normally is held by a spring 64 against an eccentric shoulder on a screw stud 65 carried by bracket 31. In this position of the 65 parts a spring 66, attached to latch 60 and arm 59, holds the latch in engagement with the lug 61. Hinged to the upper arm of lever 62 is a printing hammer 67, the type of hinge joint being such as to permit the hammer to swing only 70 in a clockwise direction (Fig. 4), a spring 68 secured to lever 62 and hammer 67 normally holding the major axes of both lever 62 and the shank of the printing hammer in substantially a straight line as in Fig. 4. The tail 69 of latch 60 75

is adapted, when arm 59 is rocked in a counter-clockwise direction to strike an eccentric shoulder on a screw stud 70, and the position of the stud is such that the latch 60 will be gradually disengaged from the lug 61 as the arm rocks as described. By rotating the stud 70 the point at which complete disengagement occurs can be regulated.

When the handle 50 is grasped and moved horizontally in slot 53 to bring pointer 61 into register with a number on plate 54 and then said handle is depressed, shaft 45 will be rocked counterclockwise (Fig. 4), rocking shaft 58 and arm 59 likewise through gears 55, 56, 57. The latch 60, by engaging lug 61, will rock lever 62 and hammer 67 counterclockwise against the tension of spring 64 until eventually the arm 63, cooperating with stud 70, will cause latch 60 to disengage lug 61 permitting spring 64 to rock lever 62 clockwise to its normal position with arm 63 abutting stud 65. When stud 65 arrests arm 63 the momentum of the hammer 67 causes it to pivot slightly on lever 62 against the tension of spring 68 with the result that the hammer head strikes percussively and is immediately restored by spring 68. Normally the hammer head is clear of the type wheels as shown in Fig. 4. The restoration of arm 63 to the position of Fig. 4 is partly effected by a torsion spring 71 surrounding shaft 58, said spring being secured at one of its ends to a collar 72 and at the other end to the bracket 31 and tends to rock arm 63 in a clockwise direction (Fig. 4).

The casing 26 in front of the clock 28 and over the printing mechanism is provided with a depression or recess 73 having a slot 74 directly over the space between the type wheels and the head of hammer 67. Suspended from the flat surface of the recess 73 and projecting downwardly through slot 74 into the space between the type wheels and hammer 67 is a card chute or guide 75 which has a wide mouth 76 to receive a suitable card 77 (Fig. 4) such as the one shown in Fig. 8. The card chute 75, as shown in Fig. 1, is open at the bottom and formed with two parallel guides each extending downwardly to one side of the type wheels. This card chute guides a card into position to receive imprints from the type wheels.

The present invention has means to selectively control printing on successive lines of a card whereby the starting and stopping time of several operations may be recorded on the same card. This means is best shown in Figs. 1, 2, 4, and 6. Rotatably mounted on the frame 21, and projecting through a hole in casing 26, is a short shaft 78 to the inner end of which is secured a pinion 79 while a knurled knob 80 and a pointer 81 are secured to the end outside casing 26. The pointer cooperates with a suitable dial 82 on which are marked words and numbers to correspond with those in the extreme left hand column of the card 77 (Fig. 8) under the heading "Oper.", signifying "Operation". Each of the five numerals has associated therewith two separate positions, one the starting position and the other the stopping position. Altogether there are ten positions on dial 82 corresponding to ten lines on the card 77. Obviously this arrangement is purely arbitrary as any number of positions may be provided, as desired.

The pinion 79 meshes with a rack 83 which is vertically slidable, being guided in its movements

by two studs 84. The lower end of rack 83 has secured thereto a post 85 carrying an arm 86 which extends forwardly (to the left, Fig. 4) to a point slightly to the left of the lower part of chute 75 (Figs. 1 and 2). The arm 86 is bent to a right angle to form an arm 87 which extends horizontally below and in front of the type wheels and between the lower parts of the chute 75. This arm 87 has two offset lugs 88 which lie in the path of movement of a card dropped into the chute 75 but are to one side of the type wheel to avoid interference with the latter. It is plain that rotation of knob 80 in the proper direction will cause the two lugs 88 to move up or down to position a card for receiving an imprint on the line corresponding to a selected start or stop position on dial 82.

A suitable inking ribbon 89 is interposed between the chute 75 and the type wheels and may be wound on spools 90 mounted on a frame 91 suitably supported by the main framework. The ribbon 89 may be automatically fed by any well known mechanism for that purpose which may include a ratchet 92 and a pawl 93 operated by suitable connections to the shaft 45 or an associated part. The ribbon feed mechanism has not been illustrated in detail as it forms no part of the present mechanism and can be of any well known form.

The description so far has been mainly concerned with the printing mechanism and the connections to the handle 50 for operating said printing mechanism. The mechanism for controlling the type wheel 35 to print the elapsed time will now be described together with the connections to handle 50 for selecting an elapsed time unit for operation.

As was stated before herein, the recorder has ten elapsed time units each being more or less self contained to permit quantity production of recorders in various capacities to suit the needs of users. Each unit is mounted between a pair of adjacent partition frame plates 25 to all of which plates are common the shafts 30, 36, 45, a shaft 94 and two tie rods 95, 96. The lever 49 carrying handle 50 is shaped to form a gear sector 97 having gear teeth 98 adapted to mesh with pinions 99 secured to shaft 94. There is a pinion 99 for each elapsed time unit, one of which units is generally designated 100 in Fig. 2 and is separated from adjacent units by the partition frame plates 25. These elapsed time units are all alike and a description of one will suffice for all.

The pinions 99 are so disposed that when lever 49 has been selectively set in alignment with a vertical slot 55 in plate 54, the sector 97 and one of the pinions 99 will be co-planar so that depression of handle 50 will cause the selected pinion 99 to rotate in a clockwise direction (Figs. 5 and 7). Normally, however, the teeth of the sector do not engage any of the pinions 99 in order to permit the handle 50 and lever 49 to be moved longitudinally of slot 53 without collision between the teeth 98 on the sector 97 and pinions 99.

Secured to one side of sector 97 is a cam plate 101 adapted, when the handle 50 is depressed to rotate one of the pinions 99, to engage and rock a cam follower 102 pivoted at 103 on a stud secured to the adjacent frame plate 25 (Figs. 2 and 9). There is a cam follower 102 for each elapsed time unit and the upper end of such follower has a pin and slot connection to an arm 104 form-

ing part of a hub 105 loosely mounted on a short sleeve 36a on shaft 36. A spring 106, attached to a pin on follower 102 and to a pin secured to the adjacent frame plate 25, holds the upper end of the follower 102 against a stop pin 107 also secured to frame plate 25.

The hub 105 has a cam surface 108 (Figs. 9 and 10) coacting with a similar but complementary cam surface 109 in a bushing 110 surrounding shaft 36 and sleeve 36a, and secured to plate 25. The cam surfaces 108, 109 are so disposed that normally hub 105 and bushing 110 are in close contact as in Fig. 9, but, when arm 104 and hub 105 are rocked clockwise from the position of Fig. 5 to the position of Fig. 7 by the action of cam plate 101 on follower 102, the relative movement between the hub 105 and bushing 110 causes said hub to move axially of shaft 36 from the position of Fig. 9 to that of Fig. 10.

Loosely mounted on sleeve 36a is a collar 111 against which presses one end of a coil spring 112 surrounding said sleeve. The other end of the coil spring bears in a recess in a hub 113 rigidly mounted on sleeve 36a and presses said hub against an arm 114 secured to shaft 36 adjacent the end of sleeve 36a. Rigidly mounted on hub 113 is a ratchet wheel 115 and rotatably mounted on the latter is a toothed escapement wheel 116. The latter is provided with a continuous flange 117 and three blocks 118 which embrace the sides of ratchet wheel 115 opposite flange 117 and prevent accidental displacement of the ratchet wheel 115 and escapement wheel 116 relative to each other axially of shaft 36. Mounted in a recess in the escapement wheel 116 is a spring-pressed pawl 119 (Fig. 5) which permits ratchet wheel 115 to rotate in a clockwise direction relative to escapement wheel 116 but prevents relative movement in the opposite sense. A spiral spring 120 (Figs. 5 and 9) is secured to the end of sleeve 36a adjacent the arm 114 of the next adjacent elapsed time unit and to a pin 121 carried by frame plate 25. The effect of this spring is to tend to rotate in a counterclockwise direction (Fig. 5) the sleeve 36a of each elapsed time unit and the ratchet wheel connected to said sleeve. This tendency is transmitted to the corresponding escapement wheel 116 by means of pawl 119. Actual movement of the ratchet wheels and their escapement wheels is controlled by mechanism about to be described.

Loosely mounted on the tie rod 95 (Figs. 5, 7 and 9) between the frame plates 25, are three-armed levers 122 which, for lack of a better term, may be called verge levers. Two of the arms 123 of the verge levers have bent-over lugs adapted to engage the teeth of the escapement wheel 116 and the lugs are so disposed that normally one of them is engaging a tooth in said escapement wheel.

Furthermore, the lugs are so spaced that a half oscillation of the verge lever permits the escapement wheel to move one-half the distance between two successive teeth. In other words, one full oscillation of a verge lever 122 permits the corresponding escapement wheel to move the distance between the centers of two successive teeth. The ratchet wheels 115 have one hundred twenty teeth while the escapement wheels 116 have only sixty teeth. Thus, one-half an oscillation of any verge lever 122 will cause the corresponding ratchet wheel 115 to move one tooth distance. The type wheel 35 and escapement wheel 116 have a theoretical capacity of

twelve hours but, as will be seen later herein, this capacity cannot be had in practice.

The third arm 124 of the verge lever 122 is bifurcated and has two offset lugs 125 cooperating with opposite sides of a single lobe cam 126 secured to a sleeve 127 loosely mounted on a stud 128 carried by frame 25. Secured to sleeve 127 is a gear 129 and an eccentric shaped cam 130. The latter is between two flat springs 131 secured to a lug 132 formed in the arm 124. As gear 129, cams 126, 130, and sleeve 127 rotate as a unit one of the springs 131 will be gradually flexed more than the other and tends to cause one of the lugs 125 in arm 124 to press more firmly against cam 126 as it rotates. Eventually, about the time the high point of cam 126 comes beneath the active lug 125, the point of maximum tensioning will be reached as in Figs. 5 and 7 and, when the active lug does fall from the high point of cam 126 into the dwell, the spring 131 which is at maximum tension will cause a half oscillation of the verge lever 122 rapidly thus allowing escapement wheel 116 and ratchet wheel 115 to move the angular distance between two adjacent teeth in said ratchet wheel.

At points half-way between those of Figs. 5 and 7, both springs 131 will be equally tensioned and both lugs in arms 123 will be at the centers of their arcs of movement but one or the other of them will still be directly engaging a tooth in the escapement wheel 116. Thus the lugs in arms 123 always engage a tooth in escapement wheel 116 except at the two places in each revolution of cam 126 where the lugs 125 are dropping from the high point to the low point of cam 126. This mechanism has been adapted in order to secure a rapid and accurate action of the arms 123 in spite of the slow speed of rotation of cam 126.

Gear 129 is in the same plane as a smaller gear 133 secured to shaft 30, the ratio being two to one, but does not normally mesh with the smaller gear. The two gears 129, 133 of each elapsed time unit may be connected for driving purposes by means of an idler gear 134 carried by one arm of a three armed lever 135 loosely mounted on tie rod 95, a spring 136, secured to another arm of said lever and to tie rod 96, normally tending to rock lever 135 clockwise to mesh idler gear 134 with gears 129, 133 as in Fig. 7. However, a latch 137 pivoted on the third arm of lever 135 normally engages a fixed lug 138 carried by frame 25 and holds lever 135 in the position of Fig. 5.

Shaft 30 and hence gears 133 of all the elapsed time units make one revolution in six minutes, that is, in one tenth of an hour. Gear 133 will obviously drive gear 129 at the rate of one revolution in twelve minutes or two tenths of an hour. Since two half oscillations of verge lever 122 are produced by one revolution of cam 126 and gear 129, it is plain that ratchet wheel 115 and escapement wheel 116 will rotate one-half the angular distance between two teeth on shaft 30.

Thus each tooth on ratchet wheel 115 represents one tenth of an hour and the number of teeth correspond exactly to the number of type 70 on the type wheel 35 which, as stated before, has a capacity of 12 hours by tenths of an hour.

The levers 135 of the different elapsed time units are selectively released under control of the handle 49 through the movement of hub 105

already described. The collar 111 (Figs. 9 and 10) is slotted to receive the end of the short arm of a lever 139 pivoted at 140 to an ear formed in ratchet wheel 115, a pin through the slotted portion of collar 111 engaging a slot in the short arm of lever 139. The free end of lever 139 is formed as a rack 141 which meshes with pinion teeth 142 formed in a stop member 143 loosely mounted on a stud 144 carried by an ear 145 formed in the ratchet wheel 115. Normally the parts just described occupy the positions shown in Fig. 9 but the axial movement of collar 111 against the pressure exerted by spring 112 causes the lever 139 to rock from the position of Fig. 9 to the position of Fig. 10 and has the effect of moving stop member 143 to a position at right angles to ratchet wheel 115 as in Fig. 10. This movement of stop member 143 is utilized to release arm 135 to permit gears 129, 133, 134 to engage.

Pivoted to the third arm of lever 135 at 146 is a bell crank 147 operated by a spring 148 and having limited rocking motion between bent-over lugs 135a formed in lever 135. One arm of bell-crank 147 is gooseneck-shaped and has pivoted thereto a member 149 having an angular stop portion 150, a finger 151 abutting the tail of latch 137, and a bent-over lug 152 limiting counterclockwise movement of member 149.

30 A spring 153, interposed between ears or lugs formed in the tail of latch 137 and in bell crank 147, has the double purpose of operating latch 137 and, through finger 151, holding member 149 in the position of Fig. 5 where lug 152 engages bell crank 147.

Normally spring 148 holds bell crank 147 up against the upper lug 135a while spring 153, acting on latch 137, holds the latter and member 149 in the positions of Fig. 5 where the vertical 40 part of stop portion 150 is in the path of movement of stop member 143 when it rotates on its pivot 144. Movement of the stop member 143 to the position of Fig. 10 causes member 149 to rock clockwise a slight amount thereby, through finger 151, releasing the latch 137 from stop 138. Spring 153 then becomes effective to rock lever 135 slightly clockwise and cause gears 129, 133, 134 to mesh.

Once gears 129, 133, 134 have become meshed 50 they remain engaged until disengaged by a movement of handle 50 identical to that which effected engagement of said gears. Thus escapement wheel 116 and ratchet wheel 115 will be periodically advanced and will accumulate increments of time of the value of one tenth of an hour. As many of the elapsed time units as may be desired can be selectively set in motion by handle 50 and lever 49 and will not interfere with each other's movements to the slightest degree. The connections whereby the type wheel 35 is differentially set according to the extent of movement of any selected elapsed time unit and the means for restoring the selected elapsed time unit to starting position will now be described in 60 detail.

There is an arm 114 for each elapsed time unit and slidably mounted on each, by a pin and slot connection, is a combination stop and latch 154 in the form of a slide adapted to move radially of 70 shaft 36 and away from the center of said shaft against the tension of a spring 155 which normally holds the slide in the positions of Figs. 5 and 9. The outer end of the slide 154 is hook-shaped and adapted to strike stop member 143 when the latter has been moved to a position other than Fig.

5 as in Fig. 7. The arms 114 of all the elapsed time units are in alignment along the shaft 36 and normally occupy the position of Fig. 5.

The shafts 36 and 94 are coupled together through a flexible connection best illustrated in Figs. 1, 2, and 4. Secured to shaft 36 is a gear 158 which meshes with a gear 159 loosely mounted on shaft 94. Rigidly mounted on shaft 94, alongside gear 159, is an arm 160 carrying a pin 161 which is in the path of movement of an ear or lug 162 formed from the material comprising gear 159. A spiral spring 163 connected to a pin on arm 160 and the hub of gear 159 normally holds pin 161 and lug 162 in close contact as in Fig. 4 so that in effect shafts 36 and 94 are coupled together through the gears 158, 159 but the spiral spring provides a yielding coupling which permits shaft 94 to continue rotating in a clockwise direction after shaft 36 has been prevented from rotation. Normally the parts occupy the positions shown in Figs. 4 and 5 in which case the "0.0" type are in printing position.

When handle 50 is depressed in the manner previously described, the gear teeth 98 in sector 97 engage and rotate a selected pinion 99 thereby rotating shaft 94 and arm 160 in a clockwise direction (Fig. 4) nearly a full revolution.

It will be assumed that operation of the elapsed time unit associated with the selected pinion 99 has been initiated by a similar previous selecting operation of handle 50 and that its ratchet wheel 115 and stop member 143 have been moved to the position of Fig. 7 corresponding, let us say, to an elapsed time of 1.5 hours. The cam plate 101 will, in the manner previously described, project stop member 143 into the path of slide 154 before shaft 94 begins to turn and the rotation of said shaft by means of handle 50 will, through gears 158, 159 and spring 163, cause shaft 36 to turn in a counterclockwise direction until slide 154 eventually strikes stop member 143 as in Fig. 7. The type wheel 35, being secured to shaft 36 will be rotated the same extent as the slide 154.

When slide 154 strikes stop member 143, further rotation of shaft 36 will be prevented and at the same time the hook in said slide will snap over said stop member. Shaft 94, however, can rotate a further distance since spring 163 will be tensioned and pin 161 will move away from lug 162 for the remainder of the revolution imparted to shaft 94 by sector 97 and pinion 99. About the end of the downward stroke of handle 50, the hammer 67 will be released as described and the elapsed time of 1.5 hours will be printed on a card inserted in chute 75. On the return stroke of handle 50, the pin 161 will be drawn back into contact with lug 162 by spring 163, and after this occurs shaft 36 will be rotated in a clockwise direction back to the starting position of Fig. 5.

Due to the fact that the hook in slide 154 has engaged the stop member 143, the ratchet wheel 115 will also be drawn back to the position of Fig. 5 by arm 114 and slide 154 against the tension of its spiral spring 120, this movement being permitted by pawl 119 on escapement wheel 116. The latter remains locked, however, and immovable due to the fact that one of arms 123 of verge lever 122 is always engaging wheel 116.

As the slide 154 returns to the position of Fig. 5 from the position of Fig. 7, the stop member 143 will strike the horizontal edge of the projection 150 and push down the member 149 and with it the horizontal arm of lever 135 far

enough to permit latch 137 to relatch said lever to stop 138 and disengage gear 134 from gears 129, 133. When slide 154 arrives at a point opposite its home position the follower 102 moves 5 back to the position of Fig. 5 and the springs 100, 112 act together to restore the stop member 143 to the position of Fig. 5. Due to the thickness of the member 143, member 149 is pushed down slightly further than the position of Fig. 5 10 until the lower lug 135a strikes lug 138, thus positively arresting both the arm 114 and lever 135. When the member 143 is restored to the position of Fig. 9, the spring 136 restores lever 135 to the position of Fig. 5 to bring the left 15 hand part of member 149 below the stop portion 151 into the plane of member 143 in readiness for restoring the elapsed time unit.

The relative movement between bell cranks 147 and levers 135 is provided to ensure release 20 of the latches 137 from lugs 138 as otherwise the friction between members 143 and 149 might prevent or retard free movement of levers 135. The relative movement between members 149 and bell cranks 147 is necessary to enable members 149 to function properly to both release latches 137 and act as stops for the restoring movements of ratchets 115.

In order to restore the handle 50 and sector 25 91 to the normal positions of Figs. 4 and 5 and to restore arms 114 to the position of Fig. 5 there is provided a spring 164 (Figs. 1 and 4) secured to a pin 165 on gear 55 and a lug 166 secured to the base 20. This spring 164, assisted by spring 71, and partly assisted by spring 163, 30 tends to rock shaft 45 and the lever 49 in a clockwise direction and is tensioned whenever handle 50 is depressed.

It is imperative that the movements of handle 35 50 be completed in both directions, that is, the handle should be fully depressed in a single stroke and also returned in the same manner. Accordingly in Fig. 3 there is shown a simple full stroke mechanism.

An arm 166 is secured to shaft 45 and has 40 pivoted to it a full stroke pawl 167 operated by a spring 168. The pawl 167 is adapted to wipe over teeth in an arcuate plate 169 mounted on studs carried by frame 24 (see Fig. 1 also). Suitable dwells are provided in plate 169 to permit reversing the movement of arm 166 only at the end of the downward and upward strokes of said arm. The operation of this full stroke mechanism is conventional and like similar mechanisms used in adding machines, cash registers, and recorders of various descriptions. Stops 170 45 serve to limit movements of the arm 166 which is normally held against the lower stop (Fig. 3) by the spring 164 already mentioned.

The operation of the various mechanisms has 50 been explained more or less fully as each mechanism was described in detail, however, for sake of completeness, a brief description of the operation of the machine as a whole will now be given. It will be assumed that none of the elapsed time units has commenced to function and all are in the position of Figs. 5 and 9 and that the shaft 30 is in motion rotating at the rate of one revolution in six minutes. It will further be 55 assumed that a blank card is to be printed like in Fig. 8.

The blank card is dropped in the chute 75 and the workman grasps the knob 80 and turns it until the pointer 81 is opposite the word "start" 70 75 associated with the numeral "3" on dial 82.

The handle 50 is next grasped and moved along slot 53 until the pointer 81 is opposite the numeral "4" (identifying the workman) and depressed as far as it will go.

The cam follower 102 of the elapsed time unit assigned to workman No. 4 will be operated by cam plate 101 during the initial movement of handle 50 and sector 97, thereby causing the stop member 143 to be projected outwardly at right angles to ratchet wheel 115 as in Fig. 10.

During this movement, member 149 will be operated to disengage latch 137 and permit gears 129, 133, 134 to engage. Since ratchet wheel 115 and escapement wheel 116 are held immovable at this time by one of the arms 123 of the verge lever 122, the stop member 143 will prevent rotary movement of arm 114 and its slide 154 from the position of Fig. 5 so that shaft 36, the type wheel 35, and gears 158, 159 will be held immovable when shaft 94 and arm 162 are rotated by sector 97. As a result arm 160 will merely tension spring 163 and will rotate clockwise nearly a full revolution, limited only by the thickness of lug 162.

During the time the shaft 94 and arm 160 are rotating, the hammer 67 is being rocked counterclockwise (Fig. 4) and is released about the time arm 166 strikes the pin 170, thereby printing the workman's number, the time 6:25 and the numerals "0.0" as in Fig. 8. The springs 71, 163, 164 act together to restore the handle 50 and the arm 160 to the positions of Fig. 4. The spring 71 also restores arm 59 and latch 60 to latching position in readiness to print a second time on the same or a different card.

It will be assumed that after about seven and one-half hours have elapsed the workman has finished the operation and again places the same card in the chute 75 and grasping the knob 80 brings pointer 81 opposite the word "stop" adjacent numeral "3" on dial 82. The handle 50 is then positioned, as before, opposite the numeral "4" on plate 54 and depressed.

This time the operations are much the same except that in this case the slide 154 will not be immediately obstructed by stop member 143 as the ratchet wheel 115 of the selected unit has moved five eights of a revolution since 6:25.

As a result shaft 36 and type wheel 35 will 50 rotate five eighths of a revolution to bring the types "7.5" to the printing point before slide 154 of the selected unit strikes and hooks over the stop member 143. Shaft 94 will continue to rotate an extent of three eighths of a revolution before arm 166 strikes the upper stop 170 about 55 which time the hammer 67 will be released to print the numeral "4", the time "1:25" and the numbers "7.5" indicating an elapsed time of seven and one-half hours as in Fig. 8.

The parts will be restored to normal position, 60 when handle 50 is released, in exactly the manner previously described, the return of arms 114 to normal position causing the slide 154 of the selected unit to draw stop 143 of said unit back to the position of Figs. 5 and 9.

Obviously any number of the elapsed time units can be set in motion by selecting movements of handle 50 and can be stopped at any desired times by similar selecting movements of said handle. Only two identical and successive selecting operations of handle 50 are required to initiate and complete a cycle of operations of a given elapsed time unit, and all printing and selective operations, save the operation of selecting the line on 70 75

the card which is to receive the imprint, are performed by a single manual member.

In practice it is impossible to obtain the theoretical full capacity of twelve hours from type wheel 35 and escapement wheel 116. In the position of ratchet 115 and escapement wheel 116 corresponding to 11.9 hours the slide 154 would obstruct outward movement of stop 143.

The position corresponding to 12.0 hours is the position of Fig. 5 and if ratchet 115 rotated a full revolution under control of the verge lever 122 back to the position of Fig. 5, the operation of handle 50 would cause type wheel 35 to move a full revolution to the "0.0" position. This would cause an erroneous imprint. In order to secure twelve hours capacity it is necessary to space the types on type wheel 35 $\frac{1}{122}$ of an inch apart and change ratchet wheel 115 and escapement wheel 116 to 122 and 61 teeth respectively.

The recorder is very flexible and can be readily adapted to different systems. For instance, Fig. 8 shows a form of card adapted to keeping records of the elapsed time of a given job requiring five operations to complete the work to be done. Each card can represent a given part in process of manufacture, a job, or an order number. The numbers in the first two columns of the card can represent operations or steps in the process of manufacture, job numbers, part numbers or even workmen. Each elapsed time unit can be assigned to a given job number, part number, operation number, or employee number depending on the cost accounting system. If desired an extra type wheel can be mounted on shaft 36 or the type wheel 35 may be widened to permit printing of the burden of jobs or operations adjacent the elapsed time. Other modifications, adaptations or uses will be apparent to those skilled in the art.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. In an elapsed time recorder, a plurality of elapsed time units, recording mechanism including an elapsed time recording element controllable by any selected unit, and selecting mechanism including a single manual operating member common to all of said units for selecting an elapsed time unit, and means actuated by said member for operating the recording element under control of the selected unit.

2. An elapsed time recorder comprising a plurality of elapsed time units; a time controlled drive therefor; clutches, one for each unit and adapted to connect its unit to the time drive; selecting mechanism including a selectively-operable manual member common to all of said units; and means between the manual member and clutches whereby a first selecting operation of said member renders a clutch effective and a similar second selecting operation renders the clutch ineffective.

3. In an elapsed time recorder, a plurality of elapsed time accumulators, a variably settable elapsed time recording element, selecting mechanism for selecting said units for operation including a single manual device operable to con-

trol the selecting mechanism to selectively initiate and terminate operation of the elapsed time units, and means operated by the manual member for sensing the setting of a selected unit and variably positioning the elapsed time recording element in accordance with the setting of the selected unit.

4. In an elapsed time recorder, a plurality of elapsed time accumulators each having an element displaceable in accordance with elapsed time, a rotatable type wheel for recording elapsed time, means between the type wheel and said elements for sensing the displacement of selected element and setting the type wheel accordingly, and means for first selecting an elapsed time accumulator for operation and then operating the first named means including a single manual member common to all the accumulators for controlling the selecting mechanism.

5. In an elapsed time recorder, a plurality of elapsed time accumulating units, time controlled means for operating said units, a manual selecting device, means controlled by a selecting operation of said device for operatively connecting a selected unit to the time-controlled means, a variably settable elapsed time recording element, and means operated by said device for sensing the accumulation of a selected unit and variably setting said recording element in accordance with such accumulation.

6. An elapsed time recorder comprising a plurality of elapsed time units, means to operate said units at a predetermined rate, and means to selectively connect said units to said operating means including a plurality of disconnectable connecting devices each associated with one of said units and a single manual member for selectively operating the connecting devices, said manual member being first manually settable to select one of the connecting devices and thereafter operable to actuate the connecting device whereby to either connect a predetermined unit to the operating means or disconnect said unit from said operating means.

7. In an elapsed time recorder, a series of elapsed time units, means to drive said units to accumulate elapsed time, a series of devices for connecting said units to the driving means or disconnecting said units from the causing means, a manual member selectively movable in one direction to select one of said connecting means for operation and movable in a different direction to actuate the connecting means.

8. An elapsed time recorder comprising a plurality of elapsed time registering units, selective starting and stopping means for said units including a single manual member common to all said units and variably movable to control the starting and stopping means to select a unit and start it in operation or terminate its operation, an elapsed time printing device common to all of said units, and means whereby the printing device is set in accordance with the elapsed time registered by a selected unit each time said manual member is operated to terminate operation of a unit.

9. In an elapsed time recorder, an elapsed time printing device, a series of rotatable elapsed time elements, time controlled means for rotating said units to measure elapsed time, means connected to the printing device for sensing the extent of rotation of a selected element and setting said device accordingly; mechanism for selectively connecting the units to the time controlled means and disconnecting them therefrom including

means for rendering a selected unit effective to control the sensing means; and means for operating both the selecting means and sensing means.

10. In an elapsed time recorder, a time controlled drive, a series of elapsed time wheels each having a stop displaced from a zero position as its wheel rotates, means associated with each wheel for rendering the drive effective to rotate said wheel, a manual member operable to selectively operate the first named means one at a time, a typewheel displaceable to record elapsed time, and means operated by said manual member and connected to said typewheel for sensing the position of the stop corresponding to a selected elapsed time wheel.

11. In an elapsed time recorder; a plurality of elapsed time units with means to drive them at a constant speed to integrate time increments, said driving means being normally ineffective to drive said units; and selecting mechanism adapted when selectively operated to render the time drive effective to drive a selected unit and including a single member common to all of said clutches for selectively controlling the selecting mechanism to initiate operation of the units one at a time.

12. In an elapsed time recorder, a plurality of elapsed time units, time controlled means for actuating the units step by step to register elapsed time, means associated with each unit and operable in two successive cycles to first connect a unit to said drive and then disconnect said unit from said drive, an operating lever common to all of said units and laterally movable to select one of the connecting means for operation and movable in a different direction to operate the connecting means.

13. In an elapsed time recorder, a rotatable elapsed time computing wheel with normally ineffective means to drive it at a constant speed to accumulate elapsed time, means for rendering the driving means effective to drive the wheel, a normally inactive stop movably mounted on the wheel, an elapsed time typewheel, an arm connected to the typewheel, and rotatably mounted adjacent said elapsed time wheel and engageable with said stop when the latter is moved into the path of the arm, an operating lever, means operated by a preliminary movement of said 50 lever for moving the stop into the path of the arm and operating the first named means, and means operated by further movement of the lever for rotating said arm until it is arrested by the stop whereby to set the typewheel in accordance with an accumulation by the elapsed time wheel.

14. In an elapsed time recorder, a rotatable elapsed time computing wheel with normally ineffective means to drive it at a constant speed to accumulate elapsed time, means for rendering the driving means effective to drive the wheel, a stop movably mounted on the wheel, a typewheel, an arm connected to the typewheel and rotatably mounted adjacent said elapsed time wheel and engageable with said stop when the latter is projected into the path of the arm, an operating lever, means operated by a preliminary movement of said lever for projecting the stop into the path of the arm and operating the first named means, and means operated by further movement of the lever for rotating said arm until it is arrested by the stop whereby to set the typewheel in accordance with an accumulation by the elapsed time wheel, a platen for taking an impression from the type wheel, and means operated by

said lever at the end of the last named movement for operating the platen.

15. In an elapsed time recorder, a rotatable elapsed time computing wheel with means to drive it at a constant speed to accumulate elapsed time, means for rendering the driving means effective to drive the wheel, a stop movably mounted on the wheel, a typewheel, an arm connected to the typewheel and rotatably mounted adjacent said elapsed time wheel and engageable with said stop when the latter is projected into the path of the arm, an operating lever, means operated by a preliminary movement of said lever for projecting the stop into the path of the arm and operating the first named means, and means operated by further movement of the lever for rotating said arm until it is arrested by the stop whereby to set the typewheel in accordance with an accumulation by the elapsed time wheel, and a latch carried by said arm and adapted to engage said stop to restore the elapsed time wheel to starting position when the lever is restored.

16. In an elapsed time recorder, a series of elapsed time accumulating elements each displaceable from a zero position to accumulate elapsed time; time controlled means adapted, when connected to said elements, to cause them to be displaced in accordance with elapsed time; a recording device common to all of said elements and adapted to record the amount of displacement of selected units, means connected to said recording device for sensing displacement of a selected element and operating the recording device in accordance with such displacement, and manually controlled selecting mechanism for selecting the unit to control the sensing means.

17. An elapsed time recorder having a plurality of elapsed time units and means to operate any selected unit to register elapsed time; a single receptacle for a record sheet and recording means cooperating with the receptacle to record elapsed time on a record sheet inserted in said receptacle, said receptacle and recording means being common to all said units; means to select one of said units for operation including a single manual member, and means operated by the manual member for operating the recording means in accordance with the elapsed time registered by the selected unit.

18. In an elapsed time recorder, a plurality of elapsed time units, elapsed time recording mechanism for recording elapsed time on a record sheet, means connected to the elapsed time recording mechanism for sensing the elapsed time registered by any selected unit and setting the recording mechanism in accordance with the elapsed time registered by the selected unit, controlling means to render the sensing means effective to sense the elapsed time registered by a selected unit, and a member operable to selectively operate both the sensing means and the controlling means.

19. An elapsed time recorder comprising a plurality of elapsed time units each of which may correspond to a workman, a printing unit including an elapsed time printing element and an element settable to print a workman's number along with the elapsed time, selecting mechanism including a selectively movable manual device for operating the selecting mechanism to selectively connect the elapsed time units to the elapsed time printing element and to selectively disconnect said units from said element, means to set the elapsed time printing element according to elapsed time registered by the selected unit, and

means whereby the operation of the manual device to select an elapsed time unit selectively sets the workman's number element.

20. An elapsed time recorder comprising a plurality of elapsed time units, a common time controlled drive for said units, selecting mechanism including a single manual member for operating the selecting mechanism to selectively connect said units to said drive and to selectively disconnect said units from said drive, a printing device operated by said member and including means controllable by said units for printing elapsed time, and means controlled by the manual member for causing the elapsed time printing means to make an impression under control of the unit selectively connected or disconnected from the drive.

21. In an elapsed time recorder, a series of elapsed time units each including an element movable to successive positions to register elapsed time, elapsed time recording means including an element settable to record elapsed time, means connected to the recording element for sensing

the successive positions of any of said movable elements, and selecting mechanism including means for rendering the sensing means effective with respect to the movable element of a selected elapsed time unit.

22. In an elapsed time recorder having a series of elapsed time units with means to operate said units to register elapsed time, controlling means associated with each unit for initiating and terminating operation of said units by the operating means, said controlling means being so constructed and arranged that two successive and similar operations of said controlling means first initiates and then terminates registration of elapsed time by the associated unit, elapsed time recording means common to all of said units, means controlled by the controlling means for setting the recording means to correspond to the elapsed time registered by said units, and a single manual member common to said units for selectively operating the controlling means and the setting means.

ALFRED L. SPRECKER.
